UNITED STATES PATENT OFFICE.

ERNEST H. THOMPSON, OF CAMBRIDGE, MASSACHUSETTS.

AUTOMATIC CHANGE-MAKING DEVICE.

Application filed March 8, 1917. Serial No. 153,305.

To all whom it may concern:

Be it known that I, ERNEST H. THOMPSON, citizen of the United States, and resident of Cambridge, Massachusetts, have invented certain new and useful Improvements in Automatic Change-Making Devices, of which the following is a specification.

This invention has relation to automatic coin boxes and more particularly to that class of devices intended to automatically deliver correct change for any denomination of coin that may be deposited therein. In devices of this class it is important not only that correct change shall be delivered in return for the particular coin deposited but also that reliable provision shall be made to prevent the delivery of change upon the deposit of a coin or blank differing even slightly in size from the particular coins that the machine is intended to handle.

The invention consists primarily in a suitable casing provided with a coin chute or passage for the reception of the coin deposited combined with appropriate coin selective and transferring means by which the appropriate coins are removed to their respective receptacles automatically, certain mechanism being co-ordinated with corresponding change delivering devices whereby upon the deposit of a coin of given denomination the correct change therefor is returned to the depositor, the automatic devices becoming inoperative to deliver change in case a coin or blank not conforming to the predetermined size should be deposited in the machine.

This and other features of the invention will be hereinafter described in detail and will be clearly defined in the claims forming part of this specification.

The machine shown in the accompanying drawings is particularly intended for use in connection with or as part of, an automatic fare box such as is disclosed in my pending application for Letters Patent of the United States No. 134,864 filed December 4, 1916. Hence portions of the casing and mechanism forming part of said automatic fare box are incidentally shown in connection with the present invention which relates only to the automatic change maker.

In the accompanying drawings is illustrated the preferred form embodying the principles of this invention in which,

Figure 1 is a rear elevation showing the

main casing or frame work of the machine, a part of the actuating mechanism being shown in section.

Figure 2 is a front elevation of the machine showing the respective coin or change-containing stacks and the change-delivering chute.

Figure 3 is a vertical sectional elevation showing the automatic coin transferring mechanism and part of the change-delivering mechanism.

Figure 4 is a front elevation showing the rear face of the vertical coin selecting passage in which are mounted the electrodes or terminals of the various electric circuits which are closed by their respective coins to render operative the automatic mechanism.

Figure 5 is a plan view of the coin-delivering slides or members, the surrounding casing being shown in horizontal section.

Figure 6 is an elevation of the plate carrying the coin-depositing run-ways by which the respective coins transferred thereto by the transfer and selective mechanism are conducted to their respective stacks or containers. The run-ways on the right-hand side are for the change maker, those on the left-hand side are for the fare box and need not be further considered in this case.

Figure 7 is a side elevation somewhat enlarged showing the automatic mechanism by which the appropriate change-delivering slides are actuated through the agency of the coin-transferring mechanism.

Figures 8 and 9 are detail views of the locking bolt by which the mechanism for actuating one of the change slides is locked against accidental operation when it is desired to actuate its companion slide independently.

Figure 10 is a perspective view showing the arrangement of the change dealing slides.

Figure 11 is a vertical section showing how the slide is cut away to prevent clogging action from thin coins.

Figure 12 is a side elevation showing a yielding connection between the solenoid plunger and the coin-transferring cross-head.

The particular form of change-making device illustrated in the drawings is especially designed to be used in conjunction with my fare box before mentioned for fare collecting purposes in connection with street railway or other service, and for that reason in-

asmuch as the casing embraces both an automatic fare box for receiving and registering fares and an independent change maker arranged side by side, the casing is given a form and construction differing somewhat from that to be used in case the change maker is constructed as a physically separate unit. It should be explained, therefore, that the hopper shown at the top 10 of the receptacle with a central funnel-like chamber is used in connection with the fare box and not in connection with the change maker.

Before giving a detail description it will aid to an understanding to state that the coin to be changed, say in this case a half dollar, a quarter dollar or a dime, is deposited in the receiving aperture or chute shown at *a* (Fig. 4) through which it rolls 15 to a narrow vertical passage *a'* formed between two parallel closely arranged vertical partitions in which are located a series of projecting ledges or fingers which form the terminals of three parallel or shunt circuits 20 which include the coil of an electromagnet *x* by which automatic action is controlled as will be hereinafter explained. The coin resting on either pair of ledges will complete that particular circuit and energize 25 the coin transferring mechanism to carry the coin rearwardly into an interior compartment *a³* whence through the appropriate run-ways the coin is conducted to its final destination. The movement of the 30 coin transferring mechanism in transferring any particular coin to the interior compartment acts to set in operation the appropriate change-delivering slide or member to deliver through the front outlet *a²⁰* 35 the appropriate change from interior coin stacks.

It is to be understood that the depositor has nothing to do beyond depositing his coin and receiving his change from the outlet or change-delivering chute since the entire action of transferring the coin to its appropriate receptacle and the delivery of the change through the outlet chute is automatically set in operation through the agency 45 of the particular coin deposited which acts to close an energizing electric circuit which furnishes the motive power for the various parts of the mechanism.

As best shown in Figure 3 the selective 50 passages and apertures are enclosed within a front wall *b* and a rear wall *f* each of which is provided with a series of bearing apertures *b'* *f'* respectively, arranged in vertical alinement to permit the movement of the plungers or push rods forming 55 part of the transferring mechanism.

Immediately behind the front wall *b* and at a distance not much greater than the thickness of the largest coin to be handled, 60 is placed a vertical partition *c* which acts

as a guide to enclose the vertical run-way or chute *a'* into which the coin drops from the receiving slot or passage *a*. A series of supporting fingers or ledges are arranged in opposing pairs on opposite sides 70 of the apertures formed in this partition for the passage of the coin. The lowermost pair of fingers *b⁴* are spaced apart so as to be separated by a distance only very slightly less than the smallest coin to be handled, in 75 this case a dime. The next higher pair of ledges or coin supports *b³* are spaced apart a distance only slightly less than the diameter of a quarter dollar so that the dime will fall between them while the quarter 80 will be arrested and supported on their opposed ends. The uppermost pair of ledges are spaced to allow the other coins to pass between while retaining the half dollar.

The respective ledges are mounted on 85 strips of insulation so that the respective circuits of which they form interrupted terminals will be closed by the contact of the coin supported thereon. These several electric circuits are connected with an electromagnet *x* whose core is energized by the closing of its circuit to attract a pivoted armature member *x²* which engages a switch member *x³* whose upward movement closes the terminals *y'* of the electric circuit 90 of solenoid *y* whose plunger *y²* is normally held upward by a compressed spring *y³* when the solenoid is inactive. The energizing of the solenoid circuit acts to draw down the plunger *y²* which acts through 95 100 suitable connections, which will be described later, for the purpose of setting in operation the various parts of the mechanism.

I prefer to employ a relay magnet for 105 controlling the solenoid because if a heavy current, such as would commonly be used for actuating the solenoid, were to be closed through the contact of a deposited coin, the arcing of such current would injure the 110 coin.

Back of the partition *c* is another vertical partition or wall *d* having a series of vertically alined apertures *a²*, *a⁴*, *a⁷* opening into the run-ways or compartments *a⁵*, *a⁶*, *a⁸*, respectively, formed by dividing ribs which project rearwardly from the rear or back surface of said partition wall. These apertures are preferably formed in inserted 115 rings tapered to a narrower diameter toward their rear ends which narrow diameter corresponds closely to the diameter of the particular coin intended to pass through such aperture so as to form a selective passage or opening capable of rejecting coins 120 that are appreciably larger than the particular coin for which said aperture is intended. In this case the ring aperture *a²* is intended for a half roller, *a⁴* for a quarter dollar and *a⁷* for dimes. 125 130

The devices for moving the coin from the ledges through the apertured partitions or walls to their respective run-ways a^3 , a^6 , a^8 comprise three horizontal idler plungers g , g' , g^2 whose front or forward ends are centrally recessed to receive the horizontal push rods h , h' and h^2 which are securely fastened in a vertical bar mechanism of a reciprocating cross-head which comprises the front bar m , a rear bar m' and upper and lower connecting tie-rods m^2 .

Idler plungers g , g' , g^2 are each of them mounted in a hollow bearing g^3 secured to the rear wall f and having rear-ward extensions g^4 , g^5 , g^6 in which are inserted laterally projecting pins g^7 which are arranged to engage the adjacent free ends of bell crank levers j , j' , j^2 mounted on a series of horizontal shafts j^3 by which the respective change delivering slides are actuated to deliver change.

The rear upright or bar m' of the reciprocating cross-head is provided with a series of vertically aligned thrust screws or abutting screws g^{10} which are horizontally aligned with the rearward extensions g^4 , g^5 , g^6 of the respective plungers so that on the return movement of the cross-head in a forward direction the idler plungers are returned to normal position, indicated in Figure 3. The cross-head is moved rearwardly by the rotation of a rock shaft o to which is secured an upright arm or lever o' pivotally connected with a link o^2 whose rearward end is pivotally connected to the bar m' of the cross-head, said arm and link forming a sort of toggle joint which acts to move the cross-head rearwardly when the rock shaft is partially rotated by the downward movement of the solenoid plunger. The solenoid plunger is slotted and provided with a cross pin y^8 which is engaged by a forked lever g^{20} secured to said rock shaft o . When the solenoid y is energized through the closing of its circuit by means of the relay switch x^3 it acts to pull down the plunger y^2 which in turn partly rotates the rock shaft o thus moving the cross head rearwardly.

So long as no coin is interposed between the push rods secured to the front bar of the cross-head and the aligned idler plungers the movement of the cross-head will produce no corresponding movement of the idler plungers, because in such case all the push rods will telescope into the recesses formed in the front ends of the respective idler plungers. It will, of course, be understood that no such movement of the cross-head can take place anyway unless there is a coin resting upon a pair of the coin-supporting circuit terminals or ledges.

Let us suppose that a half dollar be dropped into the machine and finds its way through the inlet chute a to the upper pair of ledges b^2 . At once the circuit of the relay magnet

x is closed by the contact of the coin on said ledges thereby causing the switch x^3 to close the solenoid circuit and to energize the solenoid coil so as to depress the plunger y^2 . The cross-head then begins to move rearwardly until the push rod h , by pressing the coin against the front end of the idler plunger g , forces that particular idler plunger back through the apertured ring a^2 , the half dollar being carried with it owing to the pinching pressure exerted by the push rod h .

When the cross-head has reached the limit of its rearward movement the return movement of the plunger due to the expansion of the compressed helical spring y^8 , serves to release the coin from this pinching action between the push rod and its plunger, and hence the coin falls into the run-way or passage a^3 , by which it is conducted to a receptacle in the bottom of the machine. As shown in the drawings, there is sufficient clearance to give a slight lost motion between the offset abutments of the cross-head comprising the push rod h and the abutment screws g^{10} so that the idler plunger does not begin to move until after the push rod has made a slight rearward traverse and does not begin to return to normal position until after the abutment screw g^{10} has moved forward for a similar distance, the object of this clearance being to ensure complete release of the coin from the two pinching members. The friction of the supporting bearing which carries the idler plunger gives it sufficient inertia to enable it to act with entire reliability.

In this operation the other idler plungers have not been actuated owing to the fact that no coin is present on their respective ledges and hence their respective push rods are free to telescope into the forward recesses without causing any movement of the idler plungers.

In a similar manner the intermediate plunger and push rod acts to transfer a quarter dollar into the passage or run-way a^6 which conducts it to the stack or coin tube a^{25} which also forms the reservoir for containing and delivering change. The lowest pair of cooperating plungers act upon the dime to transfer it through the aperture a^7 into the run-way passage a^8 which leads to the coin stack a^{10} .

A coin that is larger than a half dollar cannot pass below the uppermost ledges b^2 and cannot pass through the gauge orifice or ring a^2 . It will, however, act to close the circuit between the ledges b^2 and cause the cross-head to move. In order to prevent clogging the machine, the apertures in the partition c are made amply large to permit a blank larger than the intended coin to pass through to the rear of said partition c and as said coin cannot continue its movement through the partition d owing to

the smaller size of the gauge ring or aperture a^2 it must drop in the vertical space between the partitions c and d at the bottom of the machine. Since the cross-head 5 cannot under such circumstances make a full rearward traverse, no change is delivered on this partial movement. However, since the solenoid acts with a powerful pull, to prevent breakage or injury to the 10 parts, I prefer to connect the forked lever g^{20} to the rock shaft o by means of a yielding connection. As shown in Figure 12 the lever g^{20} is loose on the rock shaft o and is operatively connected therewith by means 15 of spring pawls g^{21} engaging notches in a gauge disk or hub g^{22} fastened to said rock shaft. This engagement is sufficiently strong to actuate the cross-head under normal conditions but is also capable of yielding to allow the lever g^{20} , which is positively connected to the solenoid plunger, to continue its movement in case the further movement of the cross-head is blocked or obstructed by a coin or blank too large to 25 pass through the apertured gauge ring a^2 . Thus the solenoid completes its downward movement and is returned by its compressed spring to normal position. This return movement releases the obstructing blank allowing it to fall between the partitions c and d , to the bottom for recovery by the depositor. 30

The switch x^3 is disengaged from the solenoid circuit terminals by the downward movement of the pin y^{12} by the thrust of the yielding spring y^{14} interposed between the head y^{15} and the tubular plunger y^{12} against which the solenoid plunger y^2 is forced. On the return of the plunger y^2 the pin y^{13} is restored to normal position by the light helical spring g^{18} . This arrangement eases the shock of impact of the solenoid plunger. 45

The change to be delivered is contained in three vertical stacks a^5 , a^{10} , a^{25} containing respectively, nickels, dimes and quarters, the stacks being arranged side by side across the machine and having their upper ends as well as their lower ends open. Beneath the 50 lower ends of the three stacks is a bed plate p above which on the side beneath the stack a^{25} is mounted a horizontal slide p' having an aperture of a size to receive a single quarter, the plate being substantially 55 of the same thickness as a quarter dollar. Said bed plate has near its front edge or end three apertures offset rearwardly from the vertical stacks but in the same vertical planes as the respective stacks, said 60 apertures being of a size to permit the respective coins to pass through into the outlet or change delivering chute a^{20} . Obviously when the slide p' containing a single quarter is pushed forwardly until its 65 aperture registers with the aperture in the

bed plate p , the coin will fall through said bed plate into the delivery chute a^{20} . To prevent the machine from operating normally to transfer the deposited coin when the change stack is empty I provide a stop device consisting of a pair of toggle members n , n' pivotally connected together. The rear toggle member n is pivotally connected to the rear end of the slide p' so as to strike against a fixed abutment n^2 of the casing when it moves forward in flat or lowered position. The forward member or tongue n' of the toggle pair passes through a slot in the side of the coin stack to abut against the lowermost coin above the level 80 of the delivery slide or plate p' . So long as there remains in the stack one coin above the level of the delivery plate this tongue member n' will be engaged by said coin and the continued rearward movement of the 85 slide p will cause the toggle to flex or buckle upward, thus preventing the slide from being locked against movement by reason of the stop member n striking against the fixed abutment n^2 . Conversely when there is no coin in the stack above the level of the delivery plate p' this flexing action will not occur and the further movement of the slide will be arrested. This in turn will arrest the movement of the 95 cross-head through connections hereinafter described so that the coin deposited will not pass through the partition d but when released on the return movement of the cross-head, as already described, will drop into 100 the vertical passage between the partitions c and d , into the receptacle at the base of the machine which is open or accessible to the depositor, thereby enabling him to recover the coin deposited while at the same 105 time preventing the delivery of any change until the change stacks are replenished with coin.

I have now described the slide for delivering a quarter dollar. The slides for delivering the dimes and nickels act on the same principle. The dime delivering slide or plate p^2 corresponds to the thickness of a dime and has an L-shaped lateral extension or wing p^3 having an orifice aligned 110 with and beneath the lower end of the nickel stack so that upon each complete traverse this slide p^2 will deliver, side by side, a dime and one nickel. Beneath the extension p^3 of the so-called dime slide is 115 a nickel slide p^4 which corresponds in thickness to the thickness of two nickels. Hence, in normal position, the two lowermost nickels rest upon the bed plate p enclosed within the aperture in the nickel 120 slide p^4 while the third nickel from the bottom rests upon the upper of these two nickels and is included within the aperture of the extension p^3 of the dime slide p^2 . The extension p^3 has a slot p^5 extending 125

- from the rear side of its aperture to the rear edge of the extension so as to permit the forward toggle member or tongue n' to abut against the nickel contained in the aperture of the extension p^3 in order to block further action of the nickel slide p^4 when there are less than three nickels remaining in the nickel stack. It will be understood that the quarter slide operates always to deliver only one quarter at each complete traverse, that the dime slide, so-called, operates at each complete traverse to deliver a dime and one nickel and also that the nickel slide always delivers two nickels at each complete traverse. It should also be understood that the nickel slide will operate alone independently of the other slides but that movement of the dime slide always involves the simultaneous movement of the nickel slide so that whenever the dime slide acts to deliver fifteen cents the nickel slide must also act to deliver ten cents change. Furthermore while the dime slide and the nickel slide may act while the quarter slide is at rest, yet the actuating connections hereinafter explained make it necessary that both the dime and the nickel slides shall operate simultaneously with the quarter slide whenever the quarter slide is actuated.
- The result of this arrangement is that on the deposit of a dime, two nickels are automatically returned to the depositor for change but on the deposit of a quarter one dime and three nickels are returned to the depositor. On the deposit of fifty cents the depositor receives one quarter dollar, one dime and three nickels.
- I will now explain the actuating connections by which the slide movements are controlled for delivering change.
- The nickel slide p^4 has a rearwardly extending actuating rod p^{14} connecting to the downwardly extending forked arm p^{24} of a bell crank lever whose upper arm p^{34} is pivotally attached to a vertical link r whose upper end is pivotally connected to the bell crank lever j^2 that is actuated by the extension g^6 of the dime actuated plunger g^2 . Obviously the rearward movement of the plunger g^6 rocks the bell crank lever j^2 rearwardly, thereby depressing the link r and causing the connecting rod p^{14} to move forward which forces the nickel slide forward until its nickel containing aperture registers with the corresponding aperture in the bed plate p to allow the two nickels therein to fall into the chute a^{20} .
- In the same manner the rod p^{12} is moved forward by the bell crank lever p^{22} , p^{32} , when the link r' which connects arm p^{32} with arm j' is depressed by the rearward motion of the plunger g^6 . In a similar manner the slide rod p^{11} is moved forward
- through the connecting arms p^{21} , p^{31} , the link r^2 and the arm j which is actuated by the uppermost plunger g against which the half dollar is forced.
- It is to be further noted that the arm p^{34} has a laterally projecting finger p^{35} overlapping the arm p^{32} so that the arm p^{34} while free to move when the arm p^{32} is at rest, must necessarily be moved by the downward movement of the arm p^{32} , thus causing both arms, and consequently both the dime and nickel slides to be actuated simultaneously. It will also be noticed that the arm p^{32} has a similar and laterally extending finger p^{38} overlapping the arm p^{31} so that whenever the arm p^{31} is actuated, the arm p^{32} must also be simultaneously actuated and likewise the arm p^{34} .
- To prevent the dime slide p^2 from being moved by frictional engagement when the nickel slide p^4 alone is intended to be actuated, I provide a locking device for positively locking the dime slide delivering mechanism in such case. As shown in Figure 8, this locking device comprises a vertical slide bolt s having an elongated aperture s' at its upper end and a projecting presser foot or arm s^2 at its lower end. On the vertical arm of the lever j' (Fig. 7) is secured a hook s^3 arranged to pass into the aperture s' of the bolt s when the bolt is in raised position. When the bolt is lowered it engages the hook and locks the lever against movement. The bolt s is normally pressed downwardly by means of a compressed spring s^5 (Fig. 9) seated in a recess in the frame so as to press down against the upper face of the projecting finger s^2 . The rearward plunger extension g^6 is provided with a pin s^8 adapted to engage the inclined under face of the lip or projection s^2 of the bolt s to normally hold the bolt in raised position when all parts are in normal position of rest, thereby preventing the bolt from becoming operative. As soon, however, as the plunger g^6 moves rearwardly to actuate the nickel slide the bolt is released and instantly forms a locking engagement with the hook s^3 , thereby positively preventing the arm j' which controls the dime slide from having any movement.
- To empty all of the coin stacks in order to recover the coin therein the bed plate p may be pushed to the rear by pressure on its front face until the row of coin apertures therein registers with the open lower ends of the three stacks. In this position no support is afforded for the coins in the stack tubes and they immediately fall into the bottom receptacle of the machine.
- The coin slides are preferably made of a thickness corresponding to the thickness of a normal coin or coins that the slides are intended to carry. It often happens, however, that the thickness of a coin is mate-

rially reduced by wear. In that case when the coin aperture in the slide is in register with the open lower end of the coin stack, the next coin above the coin contained in the 5 slide may project slightly into the slide below its upper face. This would be likely to clog the slide and prevent it from operating. To avoid this difficulty the slides adjacent to one side of the apertures are bevelled or 10 thinned down as indicated in Figures 10 and 11 at p^{30} , the reduced or thin edge being cut down sufficiently to prevent the slide from having greater thickness at that point than such a worn coin would have. The result is 15 that when the slide moves back to deliver a coin from the change stack this edge of the coin aperture will not engage the next higher coin while the bevelled portion at p^{30} will act as a wedge to force up the superimposed 20 coin above the level of the body of the slide so as to allow the slide to move back without an obstruction. This is an important detail of the invention since without this or some equivalent arrangement it is obvious 25 that a thin or worn coin could block the operation of the change slide, as will be apparent from an inspection of Figure 11 which shows in dotted lines the position of the two lower coins when the lowermost 30 coin is thinner than normal.

What I claim is:

1. An automatic change-making device embracing in its construction a narrow chute or passageway for the reception of coins deposited, a series of differentially spaced coin-supporting members fixed therein at different levels, selective coin-transferring devices automatically operated through the agency of the coin deposited to transfer a 40 coin from such supporting members to a coin receptacle, a change-delivering device actuated through the agency of the coin-transferring devices to deliver the appropriate change for the particular coin deposited, substantially as described.

2. In an automatic change-making machine the combination with a vertical passageway, of differentially spaced coin supporting members mounted therein at different levels to support coins of different size respectively, transferring devices arranged to engage a coin resting upon any of said supports and acting to transfer the coin through an appropriate gauging aperture, change-delivering devices operatively connected with the coin-transferring devices, and an electric controlled actuating member for operating the coin-transferring and change-delivering devices, said actuating 55 member being electrically operated through the closing of a circuit effected by the agency of the coin when resting on said supports, substantially as described.

3. In an automatic change maker the 60 combination of a series of selective coin sup-

ports, a corresponding series of coin transferring members acting on their complete traverse to move coins from their support through selective openings to appropriate coin receptacles and acting on a partial 70 traverse only to return the coin to the depositor, a series of change delivering devices individually interconnected with corresponding coin transferring devices and acting only on the full traverse of the coin 75 transferring device to deliver the appropriate change, substantially as described.

4. An automatic coin-transferring mechanism embracing a reciprocating cross-head having sliding support in opposed casing 80 walls, a partition between said walls provided with coin gauging apertures of different sizes, slidable coin-engaging members loosely mounted to be slidable through said gauge apertures, push members secured to said cross-head in alignment with said loose coin-engaging members and acting when moved to press the coin against said coin-engaging members and transfer it through the appropriate gauging apertures, electrically actuated means for electrically moving said cross-head through the energization of an electric circuit that is closed by the coin deposited, substantially as described.

5. The combination of a series of separably operable change-delivering slides, change-containing stacks located to cooperate therewith in delivering coin, a series of separately acting coin-transferring devices, means for operatively connecting each coin-transferring device with a corresponding change-delivering slide, said means including a series of separate levers interconnected so as to allow one or more of said levers to be operated either separately by its own coin-transferring mechanism or conjointly by engagement with another slide actuating lever, substantially as described.

6. In a change-making mechanism the combination of a series of separately movable change-delivering members, an actuating lever for each of said members, said actuating levers being interconnected to permit one alone or two or more jointly to be actuated by a single coin deposited, coin-transferring devices automatically operated through the agency of the particular coin deposited and having operative connections with said change-actuating levers to cause them to be automatically operated singly or together, according to the value of the coin deposited and by the agency of such coin deposited, substantially as described.

7. In a change-maker the combination of a coin-receiving chute for receiving coins of different denomination, a narrow vertical passageway connected therewith for the passage of coins and, having pairs of differentially spaced coin-supporting ledges forming terminals of a solenoid controlling cir-

- cuit, said chute being provided between each pair of ledges with a lateral coin-gauging aperture; a horizontally reciprocating cross-head, a series of movable plungers opposite each aperture forming in connection with said cross-head, coin-receiving and transferring mechanism; a series of coin-stacks for containing coins of different denomination, 5 containing slides cooperating with the coin-delivering slides 70
- 10 respective coin-stacks and actuating mechanism connected with the respective plungers of the coin transferring mechanism to deliver coins from the appropriate coin stacks when a coin of appropriate denomination 15 has been transferred through its appropriate gauging orifice, the coin-transferring mechanism being operated through the agency of a coin when deposited on a pair of said ledges, substantially as described.
- 20 8. In a change-maker the combination with selective coin-transferring devices for transferring coins of different size through appropriate gauging apertures to a coin receptacle, a series of coin-containing stacks, 25 separately movable coin-delivering members cooperatively arranged with relation to said coin stacks to remove a predetermined number of coins therefrom, the respective coin-delivering members being operatively connected with the appropriate coin-transferring mechanism by 30 means of a yielding connection to permit said plunger to complete its traverse when the coin transferring mechanism is obstructed by a coin or blank of inappropriate size, substantially as described.
- 35 9. In a change making device the combination of selective coin positioning devices, 40 a series of coin transferring devices co-ordinated to remove coins from said positioning devices through selective apertures, a series of change delivering devices interconnected 45 respectively with the different coin transferring devices and acting to deliver the appropriate change only after the coin transferring devices have carried the appropriate coin through the selective openings, substantially as described.
- 50 10. In a change-making mechanism the combination with selective coin-transferring devices arranged to transfer coins of different predetermined sizes through selective 55 gauging apertures, change-delivering mechanism interconnected with said coin-transferring devices to deliver the appropriate change for the particular coin so transferred, an actuating device comprising a 60 solenoid whose movable plunger is operatively connected with the coin-transferring mechanism, and a switch for controlling the solenoid circuit, an electro-magnet for closing said switch, the circuit of said magnet 65 being closed by the coin deposited, a mov-
- able switch-releasing member normally held at inoperative position and arranged to be forced against the switch by the solenoid plunger in the last portion of its traverse in order to break the solenoid circuit, substantially as described. 70
11. The combination of coin-selecting and transferring devices, change-delivering devices operated by means of a solenoid which is energized through the agency of a deposited coin operatively connected therewith, an actuating rock-shaft, an actuating lever mounted thereon and having connection with the said rock shaft through the medium of a yielding pawl, an electric solenoid whose plunger is operatively connected with said actuating lever to move the same when the solenoid circuit is energized, substantially as described. 75
12. In a coin box the combination with a coin chute for receiving a deposited coin, coin transferring mechanism electrically operated through the agency of the deposited coin for transferring said coin to a receptacle, actuating mechanism for said coin, transferring mechanism embracing a solenoid plunger and switch operating means controlling the solenoid circuit, means actuated by the said plunger for opening the switch, said opening means having a yielding shock absorbing member interposed between itself and the plunger, substantially as described. 80
13. In a coin box the combination of a coin transferring mechanism, a solenoid whose plunger forms the actuating member for operating said coin transferring mechanism, an automatically operated switch controlling the solenoid circuit, means operated by the solenoid plunger for operating said switch, and a spring pressed member interposed between the solenoid plunger and said switch opening and means whereby a yielding resistance is interposed between the switch opening member and the plunger, substantially as described. 85
14. In a change-making device the combination of a coin-receiving chute, coin selecting and coin-transferring mechanism for transferring the deposited coins through gauging orifices to an appropriate receptacle, said transferring mechanism embracing separate independently movable plungers, a series of change delivering slides, interconnecting levers for connecting each slide with its corresponding plunger whereby, after the transfer of a gauged and selected coin, the appropriate slide is actuated to deliver change therefor; an actuated solenoid energized through the agency of a coin deposited in said chute, substantially as described. 90
15. An automatic change maker embracing in combination a coin receiving chute, a series of differently spaced coin supporting 110
- 120
- 125
- 130

members forming terminals of an electric circuit, a series of coin transferring devices arranged to seize the respective coins when on their supports and carry them through 5 selective openings, a series of coin delivering slides interconnected with the respective coin transferring devices and operated thereby to deliver the appropriate change when the coin transferred has passed 10 through the selective orifice, and actuating means for moving said coin transferring devices comprising a solenoid whose energizing circuit is controlled through the agency of the coin resting upon said supporting 15 terminals, operatively connected with said transferring devices, substantially as described.

16. An automatic change making device

embracing in combination coin positioning and selecting members arranged in a coin 20 chute, laterally movable coin transferring devices each of which moves through a selective aperture, a series of change delivering slides interconnected with the respective coin transferring devices and actuated 25 thereby after the coin has passed through the second selective aperture the entire mechanism being automatically operated through the agency of electric circuits controlled and energized through the agency 30 of a deposited coin, substantially as described.

In witness whereof, I have subscribed the above specification.

ERNEST H. THOMPSON.
